[57] CLAIM

The ornamental design for a sports scoreboard, as shown and described.

DESCRIPTION

FIG. 1 is an isometric view of a sports scoreboard showing our new design;

FIG. 2 is an end elevational view, the opposite end being the same in appearance as the end shown;

FIG. 3 is a front elevational view;

FIG. 4 is a top plan view, the bottom being the same in appearance as the top; and

FIG. 5 is a rear elevational view.
